M. H. HARTZELL

FOLDING UMBRELLA

Filed Jan. 29, 1923

INVENTOR:

Morris H. Hartzell
BY
Giedersheim & Garber & Co.
ATTORNEYS.

UNITED STATES PATENT OFFICE.

MORRIS H. HARTZELL, OF PHILADELPHIA, PENNSYLVANIA, ASSIGNOR TO SAMUEL S. FRETZ, SR., OF PHILADELPHIA, PENNSYLVANIA.

FOLDING UMBRELLA.

Application filed January 29, 1923. Serial No. 615,505.

To all whom it may concern:

Be it known that I, MORRIS H. HARTZELL, a citizen of the United States, residing in the city and county of Philadelphia, State 5 of Pennsylvania, have invented a new and useful Folding Umbrella, of which the following is a specification.

My invention relates to a folding umbrella (or parasol), the same having its ribs 10 formed of sections which are connected by hinge or pivotal joints which retain the ribs firmly in operative position in the open condition of the umbrella (or parasol), and which permit certain sections of the 15 ribs to be readily and properly folded one with the other, without the employment of springs for holding purposes.

It consists also of novel means for stiffening and strengthening the pivotal joints of 20 the sections of the ribs and retaining said means firmly in position on the respective members of said joints.

The invention is satisfactorily illustrated in the accompanying drawing, but the important instrumentalities thereof may be varied, and so it is to be understood that the invention is not limited to the specific details shown and described, as long as they are within the scope of the claims.

30 Figure 1 represents a side elevation of a portion of an umbrella frame in open condition embodying my invention.

Figure 2 represents a side elevation of said frame in folded condition embodying 35 my invention.

Figure 3 represents a side elevation of the members of the joint of the section on an enlarged scale.

Figure 4 represents a side elevation there- 40 of at a right angle to Figure 3.

Figure 5 represents a transverse section of a portion on line 5—5 Figure 3.

Figures 6 to 9 inclusive represent perspective views of detached members of the 45 device embodying my invention.

Similar numerals of reference indicate corresponding parts in the figures.

Referring to the drawings.

1 designates a rib of an umbrella, the 50 same being formed of sections 2 and 3 which are connected by the pivot 4 whereby the sections form a continuity of each other in the normal condition of the rib as shown

in Figure 1, and the section 2 may be folded on the section 3, as in Figure 2, for the 55 purpose of folding the umbrella.

Firmly clamped on the adjacent ends of the sections are the sleeves 5 and 6 respectively. On the inner terminal of the sleeve 5 are the ears 7, and on the inner terminal 60 of the sleeve 6 are the ears 8, the ears 7 being spread apart so as to freely embrace the ears 8, the latter being somewhat 65 brought together for the purpose, said ears 8 and 7 having openings 9 therethrough for 70 the insertion of the pivot 4 which is headed on the ears 7, thus forming a hinge of the sections. Furthermore, the sides of the ears 7 are inturned forming lips 7^a which are 75 adapted to bear resiliently against the adjacent side portions of the ears 8, thus providing a friction joint for said ears and consequently for the sections, serving to hold the sections firmly in the operative position in the open condition of the umbrella and 80 avoiding the use of springs for the purpose as heretofore practiced.

On the pivotal terminals of the ears 8 are the shoulders 10 which are adapted to abut the adjacent portion of the sleeve 5 as a 80 stop for limiting the upward motion and position of the section 2 in the open condition of the umbrella, as most plainly shown dotted in Figure 4.

The stretcher 11 is connected with the 85 runner 12, and section 3 as at 13, usual in such cases.

Within the ears 8 and the sleeve 6 and clamped by the same is the member 14 consisting of a plate of metal or other suitable 90 material which extends in the longitudinal direction of the rib and is seated in the channel of the section 3 thereof. One end 15 of said member 14 has therein the opening 16 for the passage therethrough of the pivot 4. 95 The other end thereof has thereon the eye 17 for connection of the cover of the umbrella, said eye abutting the adjacent end of the sleeve 6 and this with the pivot retains said member firmly in position and vastly stiffens 100 and strengthens said sleeve 6 and ears 8, and consequently one member of the hinged joint of the sections.

Within the ears 7 and the sleeve 5 and clamped by the same is the member 18 consisting of a plate of metal or other suitable 105

material which extends in the longitudinal direction of the rib and is seated in the channel of the section 2 thereof.

One end of said member 18 has thereon 5 the tongue 19, and the other end thereof has thereon the eye 20 for connection of the cover of the umbrella, said eye and tongue being adapted to abut the relative ends of the sleeve 5 and so being firmly retained in position, thus vastly stiffening and strengthening said sleeve 5 and ears 7, and consequently 10 the other member of the hinged joint of the sections, it being evident that the sections are firmly connected by said joint and so 15 held in proper positions when the umbrella is opened as in Figure 1.

In folding the umbrella, the section 2 is folded on the section 3, it turning on the pivot 4, the parts then assuming the positions as shown in Figure 2, the cover then 20 folding on the sections, as usual in such cases.

Having thus described my invention what I claim as new and desire to secure by Letters Patent, is:—

1. In a rib for a folding umbrella formed of sections, sleeves on the sections, and ears on the sleeves, and a pivotal connection for said ears, the ears of one of said sleeves hav-

ing thereon inturned lips which are adapted 30 to engage resiliently with the ears of the other sleeve forming a friction joint for the sections in the open condition of the umbrella.

2. A rib for a folding umbrella formed of 35 sections, sleeves connectible with a section and provided with pivotal ears, and a device for strengthening the sleeve and ears consisting of a plate within said ears and sleeve connected at one end by the pivotal 40 member and provided at the other end with an eye with which latter the cover of the umbrella is securable, said eye being adapted to abut the adjacent end of said sleeve.

3. A rib for a folding umbrella formed of 45 sections, sleeves connectible with a section and provided with pivotal ears, and a device for strengthening the sleeve and ears consisting of a plate within said ears and sleeve and having at one end a tongue and at the 50 other end an eye with which latter the cover of the umbrella is securable, said eye and tongue being adapted to abut the opposite adjacent ends of said sleeve.

MORRIS H. HARTZELL.
